(57) **CLAIM**

The ornamental design for a lighting remote control, as shown and described.

DESCRIPTION

FIG. 1 is a top perspective view of a lighting remote control; FIG. 2 is a bottom perspective view of the lighting remote control;

FIG. 3 is a front view of the lighting remote control;

FIG. 4 is a rear view of the lighting remote control;

FIG. 5 is a right side view of the lighting remote control;

FIG. 6 is a left side view of the lighting remote control;

FIG. 7 is a top view of the lighting remote control; and,

FIG. 8 is a bottom view of the lighting remote control.

The broken lines of FIGS. 1-2 and 7-8 illustrate portions of the lighting remote control that form no part of the claimed design.

1 Claim, 6 Drawing Sheets
